UNITED STATES PATENT OFFICE.

FRITZ WEVER, OF STUTTGART, GERMANY, ASSIGNOR TO UNION SPECIAL MASCHINEN-FABRIK, G. M. B. H., OF STUTTGART, GERMANY, A CORPORATION OF GERMANY.

BAR-EDGING SEWING-MACHINE.

1,210,125.

Specification of Letters Patent. Patented Dec. 26, 1916.

Application filed August 26, 1913. Serial No. 786,731.

To all whom it may concern:

Be it known that I, FRITZ WEVER, a subject of the Emperor of Germany, residing at Stuttgart, in the Kingdom of Wurttemberg, 5 Germany, have invented certain new and useful Improvements in Bar-Edging Sewing-Machines, of which the following is a description, reference being had to the accompanying drawing and to the figures of 10 reference marked thereon.

The invention relates to new and useful improvements in sewing machines for forming an edging and stitching the same to a body fabric.

15 An object of the invention is to provide a plurality of pairs of needles and coöperating thread laying devices and also a separate thread laying device for forming connecting loops or threads for joining the 20 groups of loops made by the different pairs of needles.

25 A further object of the invention is to provide a machine of the above character with a thread guide for forming an edging loop or scallop which is secured by one of the 30 groups of loops formed by one pair of needles.

These and other objects will in part be obvious and will in part be hereinafter more 35 fully described.

In the drawings:—Figure 1 is a front view of a sewing machine embodying my improvements; Fig. 2 is a view, partly in section and partly in plan, of the parts immediately above the work support; Fig. 3 is an end view of the machine, certain of the parts being omitted for the sake of clearance; Fig. 4 is a view, partly in section and partly in end elevation, showing the means for operating the thread guides; Fig. 5 is a view, partly in section and partly in top plan of the machine; Fig. 6 is a perspective view showing the needle head, the needles and one of the thread laying devices which coöperates with one pair of needles; Fig. 7 is a view showing diagrammatically the thread guides and the purpose of each thread guide; Fig. 8 is a diagrammatic view showing the relative movements of the thread guides and

their relation to each other; Fig. 9 is a plan view showing the finished edging made in accordance with the diagrammatic views shown in Figs. 7 and 8; Fig. 10 is a diagrammatic view, showing the thread guides operated to join two fabric sections; Fig. 11 is a plan view of two fabric sections joined in accordance with the diagrammatic illustration in Fig. 10; Fig. 12 is a view showing diagrammatically the relative position of the fabric, the looper thread loops and the thread guide loops and also the edging loop; Fig. 13 is a detail showing more or less diagrammatically needles, the work support and the loopers which coöperate with the needles.

The invention, as shown in the drawings, is embodied in a sewing machine consisting of a frame 1 carrying a main shaft 2 which is operated by the usual driving pulley 3. On the main shaft is an eccentric 4 which operates through an eccentric strap 5 to oscillate a needle lever 7 pivoted at 6 to the overhanging arm of the machine. Said needle lever is connected by a link 9 to the needle bar 8. At the lower end of the needle bar is a needle head 10 which carries the needles. In the present embodiment of the invention, the said needle head is provided with four needles arranged in two pairs 11—11 and 12—12. (See Fig. 6). The needle threads 13 pass through suitable tensions 15 and guides 16 to the needles 11—11, while the needle threads 14 pass through suitable tensions 15 and guides 16 to the needles 12—12. Coöperating with the needles 11, 11 beneath the work support is a looper L, while a looper L' coöperates with the needles 12, 12. These loopers are of the usual construction and make the well known twin needle stitch. The loopers are mounted on a looper carrier which is oscillated by a looper rod 18 which, in turn, is connected to the needle lever extension. Each looper is a thread carrying looper and enters the loops of both needles of the pair with which it coöperates so as to form connecting loops between the lines of stitching. The looper threads 62 form in

connection with the needle threads 13 and 14 the lower layer of loops or threads F, see Fig. 12.

A thread guide 19 coöperates with the 5 pair of needles 11—11, and this thread guide is arranged to oscillate over the throat plate 17. The thread 21 guided by said thread guide is laid back and forth in front of the pair of needles and is stitched 10 down by the needle threads crossing over the same. Coöperating with the pair of needles 12—12 is a thread guide 20 carrying a thread 22, which is likewise laid across from one needle to the other of the pair 15 and is stitched down by the needle threads 14. The thread guides 19 and 20 are operated from the main driving shaft through a gear 23 which meshes with a gear 25 on a shaft 24. An eccentric 26 carried by the 20 shaft 24 is connected through an eccentric rod 27 to an arm 28 on a shaft 29 mounted in suitable bearings in the overhanging arm. At the other end of the shaft 29 there is a crank 30 to which is connected a link 31. 25 The link 31 is also connected to an arm extending laterally from the vertical shaft 32 mounted in suitable bearings in the head of the machine. This shaft 32 carries the lever 33 on which is mounted the thread guide 19, 30 so that the rocking of the shaft 32 will oscillate the guide 19 in front of the needles 11—11. The operating gears are so proportioned that the thread guide 19 is moved laterally once for each complete reciprocation of the needle so that loops of thread B are laid back and forth and held by the 35 needle threads 13.

The guide 20 is carried by the lever 58. This lever 58 is loosely mounted on the shaft 40 61 and turns about the same as an axis. Said lever 58 extends in rear of its support and is connected by a link 59 to a rearwardly projecting arm on the lever 33. The movements, therefore, of the shaft 32 will 45 be transmitted through the link 59 to the lever 58, and the thread guides 19 and 20 will, through this mechanism, be moved simultaneously in one direction and then in the other, laying the threads carried by the 50 respective guides back and forth in front of the respective pairs of needles, in the manner fully illustrated in the drawings.

From the above, it will be apparent that with each pair of needles there is a looper 55 and a thread guide, and these elements coöperate to form connected rows of threads, the distance between which depends upon the distance between the pairs of needles. The two lines of stitches thus formed are 60 connected by thread loops formed in a thread 34 of an oscillating thread guide 45.

On the shaft 24 there is a gear 35 meshing with a similar gear 35^a of larger diameter

on the shaft 36 which is mounted in suitable bearings on the work support. On the shaft 65 36 there is a drum 37. A toothed segment 39 is pivoted at 38 to the work support, and this toothed segment meshes with a segment 40 formed on a lever 44 pivoted at 43 to the cloth plate. The segment 39 carries a pin 70 41 which runs in the cam groove 42 in the drum 37. This cam groove is so shaped that in each revolution of the drum the toothed segment swings about the pivot 38 and in turn oscillates the segment 40 and the lever 75 44 to which it is attached. This lever 44 has a forwardly extending arm carrying a thread guide 45 through which the thread 34 is led. Said thread guide 45 is oscillated first from one side to the other and coöperates with the inner needles of the respective pairs 11 and 12. The cam groove 42 is so shaped and the shaft 46 is so driven that the guide 45 stops while the fabric is being fed two stitches, then said guide is moved 80 to the other end of its stroke. As a consequence, loops are formed so that there are at least two stitches between the lines of thread extending from one group of connected loops to the other. In appearance, the 85 edging formed on my machine shows single rungs or bars of the center or crochet thread spaced and connecting the groups of loops formed by the pairs of needles.

In order to form an additional border or 90 ornament at the extreme outer edge or at the right hand needle of the pair of needles 12—12, I have provided a thread guide 48 which carries edging threads 56. The guide 48 is mounted on a lever 47 which is pivoted 100 at 46 to the work support. This lever is oscillated by a lever 49. Said lever 47 has a slot 50 in which a pin 51 carried by the lever 49 moves. The lever 49 is mounted on an adjustable pivot 52. A pin 53, carried 105 by the lever 49, engages a cam groove 54 in the drum 55 mounted on the shaft 36. As the shaft 36 rotates, the lever 49 will be oscillated and this, through the pin and slot connection with the lever 47, will oscillate 110 the thread guide 48. The presser foot 70 or a contact detains the edging threads 56 and coöperates in the positioning of the same for engagement by the needle.

In the operation of the machine, a fabric 115 A is fed underneath the presser foot, so that one of the needles 11 passes through the fabric while the other passes over the edge thereof. Said fabric may be guided by an edge guide 60. The needle loops are joined 120 by a looper beneath the fabric and by the thread 21 above the fabric. The two needles 12—12 form loops which are engaged by the looper, and the needle threads also join together the strands of thread 22. The groups 125 of loops joined by the pairs of needles 11

and 12, respectively, are connected by the bars C formed from the thread 34.

In Fig. 11 of the drawings, I have shown 5 joining two sections of the fabric A and E. The groups of stitches or loops B—B are made in the manner above referred to, and these are connected by the cross bars C, also made in the manner stated. This fabric section 10 E may be a lace edging.

Having thus described my invention, what I claim as new and desire to secure by Letters Patent, is:—

1. A sewing machine including in combination 15 pairs of needles, a thread carrying looper coöperating with each pair of needles, a thread guide coöperating with each pair of needles above the work support, and a third thread guide coöperating with the inside needles of each pair of needles, whereby the groups of loops formed by the respective pairs of needles and their coöperating devices are connected.

2. A sewing machine including in combination 25 pairs of needles, a thread carrying looper coöperating with each pair of needles, a thread guide coöperating with each pair of needles above the work support, and a third thread guide coöperating with the inside 30 needles of each pair of needles, whereby the groups of loops formed by the respective pairs of needles and their coöperating devices are connected, said third thread guide being timed so that the connecting threads are spaced two or more 35 stitches apart.

3. A sewing machine including in combination 40 pairs of needles, a thread carrying looper coöperating with each pair of needles, a thread guide coöperating with each pair of needles above the work support, a third thread guide coöperating with the inside 45 needles of each pair of needles, whereby the groups of loops formed by the respective pairs of needles and their coöperating devices are connected, and a fourth thread laying member coöperating with the outside needle of one pair of needles for forming a scalloped edging.

50 4. A sewing machine including in combination pairs of needles, a thread carrying looper coöperating with each pair of needles for forming loops connecting the needle loops, a thread guide coöperating with each 55 pair of needles above the work support for forming loops connecting the lines of stitching produced by the respective pairs of needles, independent means for pivotally supporting said thread guides, the pivot for 60 each thread guide being disposed centrally in rear of the pair of needles with which it coöperates.

5. A sewing machine including in com-

bination a plurality of pairs of needles, a thread carrying looper beneath the work 65 support for each pair of needles, a thread guide coöperating with each pair of needles above the work support, a third thread guide coöperating with the inside needles of each pair, the throw of each thread guide being 70 such that two groups of loops are formed and connected by a thread lying in the plane of the body fabric.

6. A sewing machine including in combination 75 a work support, a main shaft lying beneath the work support, an overhanging arm, a needle bar reciprocating in said overhanging arm and carrying a plurality of pairs of needles, a thread guide for each pair of needles, means for supporting said thread 80 guides on said overhanging arm, means for connecting the thread guides whereby they are simultaneously operated in opposite directions, means for oscillating said thread guides, a thread guide coöperating with the 85 inner needles of each pair, means for mounting said thread guide on the work support, and means for oscillating said thread guide.

7. A sewing machine including in combination 90 a work support, a main shaft lying beneath the work support, an overhanging arm, a needle bar reciprocating in said overhanging arm and carrying a plurality of pairs of needles, a thread guide for each pair of needles, means for supporting said 95 thread guides on said overhanging arm, means for connecting the thread guides whereby they are simultaneously operated in opposite directions, means for oscillating said thread guides, a thread guide coöperating 100 with the inner needles of each pair, means for mounting said thread guide on the work support, means for oscillating said thread guide, said last-named means including a shaft mounted on the work support in 105 rear of the overhanging arm, means for rotating the shaft from the main shaft of the machine, a cam on said shaft in rear of the overhanging arm, and devices operated by said cam for oscillating said thread guide 110 carried by the work support.

8. A sewing machine including in combination 115 a work support, a main shaft lying beneath the work support, an overhanging arm, a needle bar reciprocating in said overhanging arm and carrying a plurality of pairs of needles, a thread guide for each pair of needles, means for supporting said 120 thread guides on said overhanging arm, means for connecting the thread guides whereby they are simultaneously operated in opposite directions, means for oscillating said thread guides, a thread guide coöperating with the inner needles of each pair, means for mounting said thread guide on 125 the work support, means for oscillating said

thread guide, said last-named means including a shaft mounted on the work support in rear of the overhanging arm, means for rotating the shaft from the main shaft 5 of the machine, a cam on said shaft in rear of the overhanging arm, devices operated by said cam for oscillating said thread guide carried by the work support, a fourth thread guide carried by the work support, a second 10 cam on the shaft in the rear of the over-

hanging arm, and devices operated thereby for oscillating said fourth named thread guide.

In testimony whereof, I affix my signature in the presence of two witnesses.

FRITZ WEVER.
